GAUGE PLATE ASSEMBLY

Thomas W. Hays, Salt Lake City, Utah, assignor
to The Union Switch and Signal Company,
Swissvale, Pa., a corporation of Pennsylvania

Application August 28, 1947, Serial No. 770,992

8 Claims. (Cl. 238—288)

1

My invention relates to a gauge plate assembly for railway switches, and particularly to a gauge plate assembly which can be adjusted for use with any size of stock rail and with either a right-hand or a left-hand turnout.

It is a common expedient in railway switch layouts to provide one or more of the ties in the vicinity of the switch points with a gauge plate assembly for maintaining the proper angular relationship and spacing between the turnout stock rail and the through stock rail. These gauge plate assemblies usually comprise a two-part gauge plate secured to the ties underneath the rails, two riser plates one for each stock rail and each secured to or formed integrally with the upper side of the gauge plate in abutting engagement with the inner base flange of the associated rail, and two rail braces, one for each stock rail and each secured to the upper side of the gauge plate in abutting engagement with the outer side of the associated rail. It will be obvious that since one of the stock rails in each switch layout is inclined at an angle to the other, the riser plates and rail braces associated with the inclined rail must be similarly inclined in their abutting edges, and it follows therefore that the usual gauge plate assembly made up for use with a right-hand turnout rail could not be employed with a left-hand turnout rail, and vice versa.

One object of my invention is to provide a novel and improved gauge plate assembly which can be used with either a right-hand or a left-hand turnout.

Another object of my invention is to provide a gauge plate assembly of the type above referred to which can be adjusted for use with different sizes of stock rails.

According to my invention the riser plate which is adapted to abut against the inclined turnout stock rail is provided on the edge which cooperates with the turnout rail with a double taper so disposed that the one taper will bear against the rail when the gauge plate assembly is used with a right-hand turnout and the other taper will bear against the rail when the gauge plate assembly is turned end for end and used with a left-hand turnout. Furthermore, the rail brace which cooperates with the outer side of the turnout stock rail is so constructed that it can be clamped in different angular positions to enable it to be used with both right-hand and left-hand turnouts. The difference in spacing between the riser plates necessary to compensate for different rail sizes is obtained by interposing between two parts of the gauge plate an insulating joint, the

2

thickness of which is increased or decreased as required.

Other objects and characteristic features of my invention will become apparent as the description proceeds.

I shall describe one form of railway switch provided with one form of gauge plate assembly embodying my invention, and shall then point out the novel features thereof in claims.

10 In the accompanying drawings, Fig. 1 is a top plan view showing a railway switch, two of the supporting ties of which are provided with gauge plate assemblies C embodying my invention. Figs. 2 and 3 are top plan and side elevational views respectively of one of the gauge plate assemblies shown in Fig. 1. Fig. 4 is an enlarged view of a portion of one of the gauge plate assemblies shown in Fig. 1. Fig. 5 is a vertical sectional view taken on the line V—V of Fig. 1.

20 Similar reference characters refer to similar parts in each of the several views.

Referring first to Fig. 1, the reference character A designates a railway switch comprising, as usual, two fixed stock rails 1 and 1a and two movable rails or switch points 2 and 2a. The stock rails 1 and 1a are laid on tie plates 3 and gauge plates 4 secured to crossties 5 in the customary manner. The movable rails 2 and 2a are fastened together by a front rod 6 and a head rod 7, and may be moved into a normal or a reverse position by means of a throw rod 8 which is connected with the head rod 7 through the medium of a switch basket 9. When the switch occupies its normal position, in which position it is shown in the drawing, the movable rail 2 engages the stock rail 1, and the movable rail 2a is spaced from the stock rail 1a. When the switch is reversed, however, the movable rail 2a then engages the stock rail 1a and the movable rail 2 is spaced from the stock rail 1.

40 The throw rod 8 may be connected with any suitable form of switch operating mechanism B. Mechanism B forms no part of my present invention, and as here shown, it is similar to that described and claimed in Letters Patent of the United States No. 2,184,870, granted December 26, 1939, to Herbert L. Bone et al.

45 The gauge plate assemblies C embody my present invention, and as here shown, each assembly C comprises a three-part gauge plate designated as a whole by the reference character 4 and comprising two base plates 4a and 4b and a connecting plate 4c. The plates 4a and 4b are secured together in longitudinal alignment at a point intermediate the rails 1 and 1a by an insulating

joint 10, while the plate 4c is secured to the outer end of plate 4b by an insulating joint 11. All three of the plates 4a, 4b, and 4c are bolted or otherwise secured to the top of the associated tie 5 at right angles to the stock rail 1a, and since the rail 1 is disposed at an angle to the rail 1a at this tie, it will be obvious that the rail 1 crosses the gauge plate at a different angle from that at which the rail 1a crosses the gauge plate; i. e. at an angle other than a right angle.

Secured to or formed integrally with the base plate 4a is a riser plate 12, the outer edge 12a of which is adapted to abut against the inner edge of the base of stock rail 1a. The outer end of plate 4a is provided on its top surface with a butt plate 13, the inner edge 13a of which forms the abutting surface for the outer end of any suitable type of adjustable rail brace 14 (see Figs. 1 and 5). Rail brace 14 is secured to the base plate 4a between the butt plate 13 and the outer side of the stock rail 1a and serves to wedge the rail 1a against the outer edge 12a of riser plate 12 in a well-known manner.

Plate 4b is provided on its top surface with an affixed or integrally formed riser plate 15, the outer edge 15a of which is provided with a double-taper. One-half of the double-tapered edge 15a is adapted to abut against the inner edge of the base of the turnout stock rail 1 when the layout is a right-hand layout as shown, and the other half of the double-tapered edge is adapted to abut against the inner edge of the turnout rail base when the gauge plate assembly C is turned end for end and employed in a left-hand layout. The two halves of the double-tapered edge 15a make equal and opposite angles with a plane parallel to the through rail and perpendicular to the longitudinal axis of the gauge plate.

It will be apparent from the foregoing that a gauge plate assembly having an affixed riser plate, such as plate 15, for engaging the inner base flange of a switch turnout stock rail in the manner above described is capable of being employed irrespective of the direction of the rail turnout. However, when such a riser plate is employed, it is necessary in order to maintain the proper rail spacing at the particular tie location to provide a suitable means for wedging the turnout stock rail against one of the halves of the double-tapered edge 15a of the riser plate. To accomplish this wedging of turnout rail 1, I have here shown and designated generally by the reference character 16 one form of adjustable rail brace disposed on the top surface of base plate 4b adjacent the outer side of rail 1.

As best shown in Figs. 4 and 5, the rail brace 16 consists of a backer member 17 supported by the base plate 4b, a butt plate 18 affixed to the plate 4b adjacent the outer end 17a of member 17 and a wedge member 19 interposed between the tapered inner face 17b of member 17 and the outer side of rail 1. Wedge member 19 is slidably mounted on a bolt 20 extending through an elongated hole 19a in the member 19, the bolt being supported in and extending through a clearance hole in a lug 17c formed on face 17b of member 17. The outer face 19b of the wedge member is of similar taper to that of face 17b of member 17, and the inner face 19c of the wedge member is parallel to bolt 20 and shaped to cooperate with the outer side of rail 1. Wedge member 19 is secured on the bolt 20 by a nut 21 which when tightened on the threaded end of the bolt acts through spring washer 22 and flat washer 23 to move the member 19 lengthwise

and, due to the cooperation of inclined face 19b with inclined face 17b of member 17, toward the rail 1. Backer member 17 and butt plate 18 are provided with mating outer and inner ends, 17a and 18a, respectively, which are shaped along the arc of a circle whose center is the midpoint of the double tapered edge 15a of riser plate 15. Member 17 is provided with clearance holes 17d through which hold-down bolts 24 extend and which holes 17d are elongated along an arc similar to that of outer end 17a of member 17. Bolts 24 pass through clearance holes in the plate 4b and the tie is recessed at 25 (see Fig. 5) for the heads of same. Nuts 26 when tightened on the threaded ends of bolts 24 act through washers 27 to secure the backer member 17 in place on the base plate 4b.

Engagement of the turnout stock rail 1 by the rail brace 16 is effected as follows. The nuts 26 are first loosened, and the backer member 17 with attached wedge member 19 is then shifted relative to the base plate 4b to the position in which the inner face 19c of the wedge member is parallel to the rail 1. The nut 21 is next tightened on the bolt 20, thereby forcing member 19 to the position in which it is firmly wedged between rail 1 and backer member 17 and, finally, the parts are secured in place by tightening the nuts 26 on bolts 24, the position of the parts attained being that shown in Fig. 4. It will be obvious that when the gauge plate assembly C is turned end for end and employed in a left-hand switch turnout, the rail brace 16 can be similarly positioned and secured for engagement with the turnout rail merely by shifting the member 17 in the opposite direction to the position in which face 19c is parallel to the left-hand turnout rail.

As was previously pointed out, the two base plates 4a and 4b of gauge plate 4 are secured together intermediate their ends by means of an insulating joint 10. This joint functions to insulate one rail from the other and also to compensate for the slight differences in spacing between the two base plates occasioned by the use of the same gauge plate assembly with different sizes of stock rails. The construction of the joint 10 is well known, and a detailed description of this joint is therefore believed to be unnecessary for purposes of my present invention. It should be pointed out, however, that the joint is formed by clamping insulation between upturned ends 28 and 29 of plates 4a and 4b, respectively, through the medium of insulated bolts 30. In accordance with my present invention, it is contemplated that the thickness of the insulation will be either increased or decreased until the spacing between base plates 4a and 4b is such that the required track gauge between abutting edges 12a and 15a of riser plates 12 and 15, respectively, is obtained for a particular size of stock rail.

It will be obvious that the stock rail spacings at various tie locations containing the gauge plate assemblies C vary between switch layouts having different angles of turnout and also between the adjacent ties of any one layout. Therefore, if, as is usually the case, these variations in stock rail spacing are of such magnitude as to preclude the use of the same assembly C at different locations merely by varying the thickness of the insulation in the joint 10, the employment of different assemblies at different tie locations is necessitated. It will be apparent, however, that either of the base plates 4a and 4b can be maintained standard for all tie locations while the other is varied. In

the particular embodiment of my invention shown in the drawings I prefer to provide similarly constructed plates 4a and different plates 4b with riser plate and rail brace spacings varying as the stock rail spacing varies.

Each gauge plate assembly C is provided with holes 34 for receiving any suitable fastening means, such as lag screws 32, for securing the plate 4 to the tie 5 and the rail brace 44 in place on base plate 4a. Each assembly C is also provided with elongated holes 33 in the riser plates 12 and 15 through which spikes may be driven in the event it is desired to spike the switch points in the normal or reverse positions.

The part 4c of each gauge plate 4 may or may not be provided depending on whether or not the tie containing the gauge plate also serves to support the switch operating mechanism B. In the event part 4c is provided, it is attached at its outer end in any suitable manner (not shown) to mechanism B. This is considered desirable to prevent lateral movement of mechanism B on ties 5 relative to the switch.

The principal advantage of a gauge plate assembly embodying my invention is that since the same assembly can be used for both right-hand and left-hand turnouts considerable savings in manufacture costs for the assemblies can be obtained.

Another advantage of my invention is that since the same gauge plate assembly can be used with a plurality of different sizes of stock rails merely by varying the insulation thickness of the insulating connection between the two rails supporting parts of the gauge plate, the number of different sizes of assemblies required for different track installations is greatly lessened, whereby a further saving in manufacturing costs is effected. Although I have herein shown and described only one form of gauge plate assembly embodying my invention, it is understood that various changes and modifications may be made therein within the scope of the appended claims without departing from the spirit and scope of my invention.

Having thus described my invention, what I claim is:

1. Apparatus for maintaining a predetermined spacing between the two stock rails of a track switch, comprising a first rail-engaging member having a surface adapted to abut against the through stock rail and a second rail-engaging member formed with two plane surfaces making equal and opposite angles with a plane parallel to the through stock rail, one of said surfaces being adapted to abut against the turnout stock rail when the turnout is a right-hand turnout and the other adapted to abut against the turnout stock rail when the turnout is a left-hand turnout, and a gauge plate to which said members are rigidly attached.

2. Apparatus for spacing apart the two stock rails of a track switch, comprising two members for respectively engaging the opposite rails, the one of said members for engaging the turnout stock rail being formed with two tapered surfaces making equal and opposite angles with a plane parallel to the through stock rail, one of said surfaces being adapted to abut against the rail when the turnout is a right-hand turnout and the other adapted to abut against the rail when the turnout is a left-hand turnout, and means for rigidly supporting said members.

3. Apparatus for maintaining a predetermined spacing between the stock rails of a track switch, comprising a first rail-engaging member adapted

to abut against the inner edge of the through stock rail, a second rail-engaging member formed with two tapered surfaces making equal and opposite angles with a plane parallel to the through stock rail, one of said surfaces being adapted to abut against the inner edge of the turnout stock rail when the turnout is a right-hand turnout and the other adapted to abut against the inner edge of the turnout stock rail when the turnout is a left-hand turnout, means capable of wedging said turnout rail against either one of said tapered surfaces, and means for rigidly supporting said members in a definite spaced relationship.

4. In an assembly for maintaining a predetermined spacing between the two stock rails of a track switch, in combination, a gauge plate, a first riser plate affixed to said gauge plate and adapted to abut against the inner edge of the through stock rail, and a second riser plate affixed to said gauge plate for engaging the turnout stock rail, said second riser plate having its rail-engaging edge formed with two tapered surfaces making equal and opposite angles with a plane parallel to the through stock rail, one of said surfaces being adapted to abut against the inner edge of the turnout rail when the turnout is a right-hand turnout and the other adapted to abut against the inner edge of the turnout rail when the turnout is a left-hand turnout.

5. A gauge plate assembly for maintaining a predetermined spacing between the two stock rails of a railway track switch, comprising a gauge plate, means attached to the gauge plate for engaging both sides of the through stock rail to hold it fixed on the gauge plate, a riser plate attached to the gauge plate for engaging the inner side of the turnout stock rail, said riser plate having its rail engaging edge formed with two plane surfaces making equal and opposite angles with a plane perpendicular to the longitudinal axis of the gauge plate, one adapted to engage the turnout rail of a right-hand turnout and the other adapted to engage the turnout rail of a left-hand turnout, a rail brace for the outer side of the turnout rail including a butt plate attached to the gauge plate having a surface of arcuate cross-section facing the rail and with its center of curvature at the intersection of the planes of said surfaces, a backer member between the butt plate and the rail having its end facing away from the rail shaped to conform with said butt plate surface and having its end facing the rail tapered, a wedge member slidable between the backer member and the rail, and means for securing the wedge member against movement relative to the backer member.

6. A gauge plate assembly for maintaining a predetermined spacing between the two stock rails of a railway track switch, comprising a gauge plate, means attached to the gauge plate for engaging both sides of the through stock rail to hold it fixed on the gauge plate, a riser plate attached to the gauge plate for engaging the inner side of the turnout stock rail, said riser plate having its rail engaging edge formed with two plane surfaces making equal and opposite angles with a plane perpendicular to the longitudinal axis of the gauge plate, one adapted to engage the turnout rail of a right-hand turnout and the other adapted to engage the turnout rail of a left-hand turnout, and a rail brace for the outer side of the turnout rail including a butt plate attached to the gauge plate having a surface of arcuate cross-section facing the rail and

with its center of curvature at the intersection of the planes of said surfaces.

7. A gauge plate assembly for maintaining a predetermined spacing between the two stock rails of a railway track switch, comprising a gauge plate, means attached to the gauge plate for engaging both sides of the through stock rail to hold it fixed on the gauge plate, a riser plate attached to the gauge plate for engaging the inner side of the turnout stock rail, said riser plate having its rail engaging edge formed with two tapered surfaces making equal and opposite angles with a plane perpendicular to the longitudinal axis of the gauge plate, one adapted to engage the turnout rail of a right-hand turnout and the other adapted to engage the turnout rail of a left-hand turnout, and a rail brace attached to the gauge plate for engaging the outer side of the turnout rail.

8. A gauge plate assembly for maintaining a predetermined spacing between the two stock rails of a railway track switch, comprising a gauge plate, means attached to the gauge plate for engaging both sides of the through stock rail to hold it fixed on the gauge plate, a riser plate attached to the gauge plate for engaging the inner side of the turnout stock rail, said riser plate having its rail engaging edge formed with two tapered surfaces making equal and opposite

angles with a plane perpendicular to the longitudinal axis of the gauge plate, one adapted to engage the turnout rail of a right-hand turnout and the other adapted to engage the turnout rail of a left-hand turnout, a rail brace attached to the gauge plate for engaging the outer side of the turnout rail, and means for adjusting the brace toward the rail so that rails of different sizes may be clamped between the brace and the riser plate.
